(57) **CLAIM**

The ornamental design for a device for bone repair or implant fixation substantially as shown and described.

DESCRIPTION

FIG. 1 is a front view of a device for bone repair or implant fixation embodying the claimed design; the rear view being a mirror image thereof;

FIG. 2 is a left side view of the device for bone repair or implant fixation of FIG. 1; the right side view being a mirror image thereof;

FIG. 3 is an enlarged top view of the device for bone repair or implant fixation of FIG. 1;

FIG. 4 is an enlarged bottom view of the device for bone repair or implant fixation of FIG. 1;

FIG. 5 is a cross-sectional view of the device for bone repair or implant fixation of FIG. 1 taken along line 5-5 in FIG. 3; and,

FIG. 6 is a perspective view of the device for bone repair or implant fixation of FIG. 1.

The broken lines in FIG. 3 are included to indicate the cross-sectional view and form no part of the claimed design.

1 Claim, 5 Drawing Sheets
